UNITED STATES PATENT OFFICE.

JAMES B. RYAN, OF NEW YORK, N. Y.

WOVEN-WIRE MATTRESS.

SPECIFICATION forming part of Letters Patent No. 239,555, dated March 29, 1881.

Application filed November 18, 1880. (No model.)

To all whom it may concern:

Be it known that I, JAMES B. RYAN, of the city, county, and State of New York, have invented a new and useful Improvement in 5 Woven-Wire Mattresses, of which the following is a specification.

Figure 1 is a plan view of the improvement, parts being broken away. Fig. 2 is a side elevation, partly in section, through the line *x x*, 10 Fig. 1.

The object of this invention is to furnish woven-wire mattresses so constructed as to be less liable to stretch and sag than when constructed in the ordinary manner, and which 15 will not be liable to have the wire fabric pulled away from the side rails while being transported or handled.

The invention consists in a combination of woven wire, spiral and coil springs, straps, 20 and chains, by which the mattress is made more durable and less likely to sag or break from the frame, as will be hereinafter more fully described.

Similar letters of reference indicate corresponding parts.

A are the side rails, and B are the end rails, which form the frame of the mattress, and which are made sufficiently strong to withstand the strain of the wire fabric without 30 springing. The ends of the bars A B are secured to each other by bolts C, and the connection is further strengthened by metallic plates D, secured to the corners of the frame.

E is the fabric, which is formed of double 35 wires spirally coiled and interwoven with each other. The side edges of the fabric are strengthened by having the side coils formed of triple wires and more closely coiled. The inner parts of the upper sides of the end bars, 40 B, of the frame are rabbeted to receive the ends of the fabric E, which ends are flattened, and are secured to the said end bars by double-pointed tacks or staples F. The ends of the fabric E are covered by strips G, attached to 45 the rabbeted parts of the end rails, B, and which are made of such a thickness that their upper surfaces may be flush with the surfaces of the unrabbeted parts of the said end rails.

To the lower middle parts of the side rails, A, are attached the ends of one or more cross-bars, H, to which are attached the lower ends of two or more conical spiral springs, I, the top coils of which rest against the fabric E. The top coils of the springs I are connected by metal straps J', the ends of which are 50 hooked around the said top coils. The metal straps J' keep the springs I from getting out of place and support the fabric E. The cross bars or slats H support the springs I, and at the same time stiffen and brace the frame A 55 B, which frame is further stiffened by an inclined brace, K, attached to the said cross-slats H.

To the top coils of the springs I, at the head and foot of the mattress, are attached the inner 60 ends of spiral springs L, the outer ends of which are attached to the end rails, B, of the frame, to hold the springs I in place and give further strength and elasticity to the mattress.

To the side edges of the wire fabric E and 65 the top coils of the side spiral springs, I, are attached the upper ends of a number of short chains, M, the lower ends of which are attached to the side rails, A, of the frame, and which are designed to prevent the fabric E 70 from being drawn away from the side rails, A, by use or handling, or during transportation, and at the same time hold the spiral springs 75 in place.

Having thus fully described my invention, 80 I claim as new and desire to secure by Letters Patent—

1. In combination with the side frame, A, the wire fabric E, and spirals I, the chains M, connecting said fabric and spirals with said 85 side bars, substantially as described.

2. In combination with side bars, A, end bars, C, provided with rabbeted edges, cross-bars H, and brace K, the woven fabric E, chains M, spirals I, connecting straps J', and 90 coil-springs I, substantially as described.

JAMES B. RYAN.
